UNITED STATES PATENT OFFICE

163,559

PRESTITCHED BEADED SHOE WELTING

Charles F. Batchelder, Jr., Milton, Mass., assignor
to Wright-Batchelder Corporation, Boston,
Mass., a corporation of Massachusetts

Application December 22, 1950, Serial No. 13,544

Term of patent 14 years

(Cl. D7—6)

To all whom it may concern:

Be it known that I, Charles F. Batchelder, Jr., a citizen of the United States, and a resident of Milton, county of Norfolk, and Commonwealth of Massachusetts, have invented a new, original, and ornamental Design for a Prestitched Beaded Shoe Welting, of which the following is a specification, reference being had to the accompanying drawing, forming a part hereof.

In the drawing the figure is a perspective view of a prestitched beaded shoe welting, showing my novel design.

My design for a prestitched beaded shoe welting is characterized by a plurality of longitudinal rows of parallel stitching on the outer surface of said welting, contrasting in color thereto, and a corresponding plurality of stitch-receiving grooves on the inner surface thereof.

I claim:

The ornamental design for a prestitched beaded shoe welting, substantially as shown and described.

CHARLES F. BATCHELDER, JR.
